METAL COIL AND METHOD OF FORMING
THE SAMEJohn Ekern Ott, Lisle Township, Du Page County,
Ill., assignor to Acme Steel Company, Chicago,
Ill., a corporation of Illinois

Application July 7, 1939, Serial No. 283,132

4 Claims. (Cl. 242—78)

This invention relates to improvements in metal coils and its purpose is to provide a novel coil of strip material or the like which may be used with advantage in stitching or stapling machines by which the parts of fiberboard boxes and other objects are secured together by metal stitches.

This stitching material, commonly known as stapling wire, is ordinarily formed as a narrow and comparatively thin steel strap and it has heretofore been supplied to the trade in the form of a continuous strip wound on a reel to form a number of concentric and radially superimposed cylinders in each of which the metal is coiled in the form of a helix. During the process of using this material in a stapling machine or the like, the coil is mounted on an axle about which it revolves and the surrounding wire fasteners which normally hold the convolutions of the coil from unwinding are removed, thus permitting the material to be unwound as it is used. It has been found that when the stapling wire is wound and used in the manner just described, great difficulty is encountered by reason of the fact that a considerable number of the outer convolutions of the coil unwind due to their own resilience and move laterally at various angles, becoming entangled with each other so that when a pull is exerted on the free end of the stapling wire, the loops or convolutions nearest the free end enclose and bind the next adjacent convolutions, or are themselves partially enclosed and bound by adjacent convolutions so that it is difficult or impossible to rotate the coil and unwind the stapling material therefrom.

The principal object of the present invention is to overcome the above mentioned difficulties by providing a new form of coil of stapling wire, or the like, made up of superimposed cylindrical layers, each comprising a helical arrangement of convolutions which, at the time of or preliminary to being wound in the coil, have been curled on radii less than those which they assume in the wound coil, so that each convolution tends to contract about the parts of the coil enclosed within it and retains itself in proper position as a part of a cylindrical layer without any auxiliary fastening means. Another object is to provide a new method of winding a coil of metallic material, such as stapling wire, steel strapping or the like, according to which the elongated metal member is progressively curled by curling dies as it is wound on a core, so that it tends to assume a curvature of lesser radius than that which it occupies in the resulting coil and ex-

erts a clamping action on one or more enclosed convolutions, thus preventing the accidental unwinding of the coil. A further object of the invention is to provide a coil of steel strip material made up of a plurality of cylindrical layers, each comprising a series of helically arranged convolutions placed edge to edge and being normally under contractile tension so that each convolution tends to wind itself up on the material enclosed within it. Other objects relate to various features of the improved method and to details of the construction of the coil which will appear more fully hereinafter.

The nature of the invention will be understood from the following specification taken with the accompanying drawing in which one embodiment is illustrated. In the drawing,

Fig. 1 shows a side elevation of the improved metal coil of the present invention;

Fig. 2 shows an end elevation of the coil illustrated in Fig. 1; and

Fig. 3 is a view similar to that of Fig. 2 showing the type of coil heretofore used, after the wire fasteners have been removed, and illustrating the manner in which the outer convolutions of the coil become entangled with each other due to their tendency to unwind and move laterally.

The difficulty with the coils of stapling wire heretofore used will be further appreciated by reference to Fig. 3 of the drawing, in which there is shown a coil 10 made up of stapling wire 11 which is in the form of a comparatively narrow flat steel strap. This strap is wound in a coil made up of a number of cylindrical layers, one of which is shown at 12. Each layer comprises a number of convolutions or loops 12a which are arranged edge to edge in helical fashion and, the fastening devices having been removed from the coil, the outer convolutions tend to unwind and to assume the straight form which they occupied before being wound in the coil so that a number of convolutions move laterally and overlap each other in irregular fashion as shown at 13, with the result that one or more convolutions adjacent the free end 11a are clamped by overlying adjacent convolutions in such a manner that the stapling material can not be unwound from the coil and much time is lost in untangling the outer convolutions of such a coil during the operation of a stapling machine.

The improved coil 14 of the present invention is shown in Figs. 1 and 2, where it is illustrated as being made up of stapling wire 15 in the form of a flat flexible steel strap having some resilience, which is wound into a number of super-

imposed cylindrical layers 16, each formed as a helical winding made up of a plurality of connected loops or convolutions 16a. The helical windings of adjacent layers are, of course, connected with each other at the ends of the coil. A sheet 17 of cardboard or the like may be placed within the central opening of the coil and a ring 18 of cardboard or the like may be placed against one or both edges of the coil. After the coil is formed, it may be bound by surrounding wire fasteners 19 which may be readily removed, when the coil is to be used, by untwisting the ends thereof.

During the process of forming the coil shown in Figs. 1 and 2, the strip 15 is subjected to the action of curling dies which curl it on a radius less than that of the curvature which it assumes in the finished coil. This radius may be preferably slightly less than that of the core on which the coil is wound. The material of the strip 15 is somewhat resilient so that it tends to retain the curvature imparted to it by the curling operation and tends to contract about the parts of the coil enclosed within it. As shown in Fig. 1, a portion 16b of a convolution which is partially removed from the coil assumes a curvature substantially less than that of the outer layer of the coil of which it forms a part. Similarly, all of the convolutions of the coil tend to contract and to assume curvatures having radii less than the radii which they occupy in the coil, so that the convolutions of the several layers 16 retain themselves accurately in place and in close contact with the enclosed layers of the coil, even after the fastening members 19 have been removed preliminary to using the stapling material in a stapling machine. With this arrangement, the loops or convolutions 16a of the coil may be successively withdrawn without interference by other convolutions of the coil.

Although one form of the improved coil has been shown and described by way of illustration in connection with one form of an improved method of forming it, it will be understood that the coil may be formed in various ways and that the improvements of the present invention may be employed with various materials without departing from the scope of the appended claims.

5 I claim:

- 10 1. A metal coil comprising a plurality of radially superimposed layers of metallic material, each layer being formed as a continuous series of connected helical windings of said material, the windings of each layer being formed to contract on those of the next inner layer.
- 15 2. A metal coil comprising a plurality of radially superimposed cylindrical layers of cylindrical metallic material, each layer being formed as a helical winding made up of a plurality of connected helical convolutions under contractile tension.
- 20 25 3. A metal coil of normally flat strip material comprising a plurality of radially superimposed layers of said material, each layer being formed of a number of helically arranged convolutions of said material placed edge to edge, each of said convolutions being curled before winding on a radius less than that of its curvature in the coil.
- 30 35 4. The method of forming a metal coil which comprises the steps of curling an elongated metal strip and winding the strip in helical fashion on a core of greater radius than the radius of curvature imparted to the strip by the curling operation, and continuing the winding operation to form a plurality of superimposed helical layers each made up of connected helical convolutions placed edge to edge.
